UNITED STATES PATENT OFFICE.

JOHN GEORGE ROBINSON AND ROBERT ABSALOM THOM, OF FAIRFIELD, MANCHESTER,
ENGLAND.

OIL BURNER.

1,413,615.

Specification of Letters Patent. Patented Apr. 25, 1922.

Application filed June 9, 1920. Serial No. 387,669.

To all whom it may concern:

Be it known that we, JOHN GEORGE ROBINSON and ROBERT ABSALOM THOM, subjects of the King of Great Britain, and residents 5 of Fairfield, Manchester, England, have invented certain new and useful Improvements in and Relating to Oil Burners, of which the following is a specification.

This invention relates to burners for 10 atomized fuel, and has for its object to provide a burner for use with a composite fuel, such as a mixture of pulverized coal and oil.

The invention consists broadly of a burner 15 of the injector type wherein the kinetic energy of elastic fluid, preferably superheated steam, from any suitable source of supply is utilized for ensuring the ejection of the fuel in atomized form and where the elastic fluid is heated—such as would be the case if 20 steam is used—its heat is employed for reducing the viscosity of the mixture. In some cases, however, a supply of compressed air may be used and where necessary this air 25 may be heated prior to use in the burner so that its heat may be utilized for maintaining the fuel in a sufficiently fluid condition.

The invention broadly consists in the provision of an injector for colloidal fuel and 30 wherein the kinetic energy of a hot inducing fluid is employed for effecting the injection and also for reducing the viscosity of the fuel.

The burner according to our invention is 35 of the injector type and in addition to the central jet of fuel inducing fluid is provided with means whereby the fuel will be subjected to the action of a secondary supply of such fluid at a point between the central jet and the burner or ignition nozzle. This secondary supply of the inducing fluid is preferably introduced into the fuel at a velocity 40 greater than that of the fuel where it is acted upon by the inducing fluid.

A further feature of the invention consists in providing means whereby the fuel 45 will be heated in the burner as it is being fed to the central jet of inducing fluid.

In the preferred form of the burner the central jet of inducing fluid is delivered 50 into a tapering fuel delivery nozzle forming the end of an annular chamber into which the fuel is fed, and in which a length of the jet pipe extends so as to act as a heater to the surrounding fuel before it is acted upon 55 by the inducing fluid. The fuel delivery

nozzle extends into and forms the central member of an annular chamber receiving the secondary supply of inducing fluid and having a conical outlet opening into the burner or ignition nozzle. 60

The inlet to the annular fuel chamber is preferably inclined towards the rest of the burner at an angle of less than 90°.

The burner or ignition nozzle is preferably of a spatular or flattened form of gradually 65 increasing area.

A further feature of the invention consists in forming a burner of the aforesaid kind with more than one jet arranged in one casting so as to deliver fuel into a common 70 burner or ignition nozzle of flat elongated section. The fuel supply and the inlets of the primary and secondary supplies of inducing fluid being provided with controlling valves so arranged that one, a number, or 75 all of the jets can be brought into use as desired.

The burner may be provided with means for adjusting the angle of delivery in the combustion chamber of the furnace. 80

In another form of the invention the burner is provided with an axis about which the jet or jets can be rocked, and also with means for rocking it about such axis in such a manner as to give it an intermittent angular motion. 85

In the various forms of the burner illustrated by the accompanying drawings, Fig. 1 is a sectional elevation, Fig. 2 a sectional plan and Fig. 3 an end elevation of a single 90 jet burner. Figs. 4, 5 and 6 are corresponding views of a three jet burner, and Figs. 7 and 8 are side and front elevations of the fuel and steam supply system to a three jet burner. Figs. 9, 10, 11 and 12 are corresponding views of a three jet burner provided with means for adjusting its angular position, Fig. 11 being a section through the fuel passages on the axis of adjustment. 95

In these drawings *a* is the fuel inlet inclined to the axis of the burner as shown and leading to an annular fuel chamber *b*. A steam or inducing fluid pipe *c* extends axially into this chamber, its end being constructed to form a jet nozzle *e*. The nozzle *e* is made 100 conical on its outside and extends into a conical outlet forming an end of the annular fuel chamber *b*. This outlet is arranged to form a nozzle extending into an annular chamber *g* provided with a steam inlet *g'*. 110

The end of this annular chamber g is conical and opens into a burner or ignition nozzle k of flattened or spatular formation. The conical outlet of the chamber g , and the outside of the nozzle k are of such shape and dimensions that the secondary supply of steam will pass between them into the burner nozzle k at a greater velocity than the jet issuing from the nozzle f .

10 The steam inlets c^4 and g^1 are connected to the steam supply systems by any suitable unions, such as g^5 and g^6 .

The burner is divided into two main sections A and B. The section B consists of a 15 hollow cylindrical casting forming the fuel feeding chamber and which is provided with an inlet a , having a flange a^1 for connecting it to the fuel supply system. Into the rear end of the section B is screwed the steam 20 inlet pipe c having at its outer end the jet nozzle e . The fuel nozzle f is formed as a separate piece screwed into the outer end of the section B and also into the rear end of the section A co-axial with the chamber g of 25 the secondary steam supply. The burner nozzle R is formed on the section A on which is also formed the steam inlet g^1 .

A form of the multiple jet burner is illustrated in Figs. 4, 5, 6 and 7. In this example three jets are shown, it may however, be constructed with any suitable number of jets. The pipes c^1 , c^2 and c^3 of three central steam jets e^1 , e^2 and e^3 are screwed 30 into the rear of the fuel chambers b^1 , b^2 and b^3 , formed in the casting B. The section B is connected to the nozzle section A by means of flanges B^1 and A^1 and bolts or screws. Each of the fuel jets impels fuel 35 into a common burner or ignition nozzle k . The fuel nozzles f^1 , f^2 and f^3 are screwed 40 into the rear of the section A at points co-axial with the jets and the secondary steam supplying chambers g^1 , g^2 and g^3 . The arrangement and action of each jet and 45 nozzle is the same as described with reference to Figs. 1, 2 and 3.

The fuel inlet a leads to the central annular fuel chamber b^2 , while the fuel inlet a^2 communicates by means of branch passages a^3 and a^4 with the annular fuel chambers b^1 and b^3 respectively.

These fuel passages are controlled by 50 means of valves l and m arranged in a casting C secured by means of bolted flanges at one end to the main fuel supply D and to the other to the section B of the burner, and provided with hand lever operating mechanism l^1 and m^1 . It will be readily understood that by means of the 55 lever l^1 the supply of fuel to the central jet can be regulated or cut off, and that by means of the lever m^1 the supply of fuel to the two outer jets f^1 and f^3 can be controlled simultaneously, so that by this arrangement, the central jet of the two outer ones 60

or all three can be brought in use as desired.

The primary and secondary supplies of steam are controlled by means of valves P, P^1 and Q, Q^1 respectively, P being connected by piping g^8 to primary steam jet e^2 and P^1 being connected by piping g^9 to the primary steam jets e^1 and e^3 , the secondary steam supply from the valve Q being connected by piping g^7 to the secondary steam jet chamber g^2 , and from the valve Q^1 by piping g^{10} to the secondary steam jet chambers g^1 and g^3 , so that the steam supply to the jets can be controlled in a manner corresponding to the control of the fuel supply by the lever l^1 and m^1 . 75

In order to provide means for adjusting the angular position of the burning in the combustion chambers, it may be constructed as shown in Figs. 9, 10, 11 and 12. The 80 general details of the fuel and steam nozzles being the same as in the preceding example. The fuel passages on the section B are however in trunnions forming the axis about which the inclination of the burner can be 85 adjusted.

The fuel passage a of the central fuel chamber b^2 leads through the centre of a trunnion flange B^2 , while the fuel passages a^3 and a^4 of the chambers b^1 and b^3 join 90 together and lead through the centre of a trunnion flange B^3 .

The flanges B^2 and B^3 are bolted to corresponding flanges on the fuel supply pipes in such a manner that by loosening the bolts 100 the angular position of the burner can be adjusted and held in such position by tightening up the bolts.

In the form of the burner wherein it is provided with means for giving it an intermittent angular motion the flanges B^2 and B^3 are replaced by any suitable fluid tight rockable trunnion, and any suitable mechanism provided for imparting the desired angular motion to the burner about 110 these trunnions.

What we claim and desire to secure by Letters Patent is:—

1. An injector burner comprising a casing, chambers in said casing arranged in pairs, the chambers in a pair being disposed one behind the other, a steam jet extending centrally through the rear chamber of each pair, means for feeding fuel to said rear chamber, an outlet in the front end of the front chamber of each pair, a conical tube connecting the rear chamber with said outlet so as to leave an annular space between said conical tube and outlet, and means for supplying steam under pressure to said front chamber which steam is caused to issue in the form of a jet from said annular space thereby forming, with the other steam jet, two steam jets of different velocities in connection with each pair of chambers 115

120

125

130

bers, the rear jet discharging into the said conical tube, substantially as specified.

2. An injector burner comprising a casing, chambers in said casing arranged in pairs, 5 the chambers in a pair being disposed one behind the other, a steam jet extending centrally through the rear chamber of each pair, means for supplying said jet with steam, means for feeding fuel by gravity to 10 the said rear chamber, an outlet in the front end of the front chamber of each pair, a conical tube connecting the rear chamber with said outlet so as to leave an annular space between said conical tube and outlet, 15 means for supplying steam under pressure to said front chamber which steam is caused to issue in the form of a jet from

said annular space thereby forming with the other steam jet, two steam jets of different velocities in connection with each pair 20 of chambers, the rear jet discharging into the said conical tube, and valve means for controlling the supply of fuel to each said rear chamber and the steam to both said steam jets whereby each pair of jets may 25 be used separately or together, substantially as specified.

In testimony whereof we affix our signatures in presence of two witnesses.

JOHN GEORGE ROBINSON.

ROBERT ABSALOM THOM.
